(57) **CLAIM**

The ornamental design for a wick for candle or other lighting apparatus, as shown and described.

DESCRIPTION

FIG. 1 is a perspective view of a first embodiment of the wick for candle or other lighting apparatus;

FIG. 2 is a top plan view of the first embodiment of the wick for candle or other lighting apparatus;

FIG. 3 is a perspective view of the first embodiment of the wick for candle or other lighting apparatus;

FIG. 4 is a top plan view of the first embodiment of the wick for candle or other lighting apparatus;

FIG. 5 is a perspective view of the first embodiment of the wick for candle or other lighting apparatus;

FIG. 6 is a perspective view of the first embodiment of the wick for candle or other lighting apparatus;

FIG. 7 is a perspective view of the first embodiment of the wick for candle or other lighting apparatus;

FIG. 8 is a perspective view of a second embodiment of the wick for candle or other lighting apparatus;

FIG. 9 is a top plan view of the second embodiment of the wick for candle or other lighting apparatus;

FIG. 10 is a perspective view of the second embodiment of the wick for candle or other lighting apparatus;

FIG. 11 is a top plan view of the second embodiment of the wick for candle or other lighting apparatus;

FIG. 12 is a perspective view of the second embodiment of the wick for candle or other lighting apparatus;

FIG. 13 is a perspective view of the second embodiment of the wick for candle or other lighting apparatus; and,

FIG. 14 is a perspective view of the second embodiment of the wick for candle or other lighting apparatus.

Any broken lines in the drawings, including both dashed and dotted lines, depict environment and/or disclaimed subject matter and form no part of the claimed design.

1 Claim, 4 Drawing Sheets
